US00D999033S

(12) **United States Design Patent** (10) **Patent No.:** **US D999,033 S**
(45) **Date of Patent:** **** Sep. 19, 2023**

(54) **APPLICATOR**

(71) Applicant: **OMS Investments, Inc.**, Los Angeles, CA (US)

(72) Inventors: **Randy M. Goodwin**, Grove City, OH (US); **Paul Havlovitz**, Dublin, OH (US); **Ryan R. Berger**, Columbus, OH (US); **Paul Hsu**, Lewis Center, OH (US); **Michael T. Kopczewski**, Grove City, OH (US); **Timothy Michael Martin**, Westerville, OH (US); **Jay F. Perkins**, Pickerington, OH (US)

(73) Assignee: **OMS Investments, Inc.**, Los Angeles, CA (US)

(**) Term: **15 Years**

(21) Appl. No.: **29/710,832**

(22) Filed: **Oct. 25, 2019**

Related U.S. Application Data

(63) Continuation of application No. 29/674,494, filed on Dec. 21, 2018, now Pat. No. Des. 864,679, which is a continuation of application No. 29/612,989, filed on Aug. 7, 2017, now Pat. No. Des. 852,593, which is a continuation of application No. 29/591,145, filed on Jan. 17, 2017, now Pat. No. Des. 797,529, which is a continuation of application No. 29/532,941, filed on Jul. 13, 2015, now Pat. No. Des. 779,898, which is a continuation of application No. 29/475,913, filed on Dec. 9, 2013, now Pat. No. Des. 736,577, which is a continuation of application No. 29/433,244, filed on Sep. 27, 2012, now abandoned, which is a (Continued)

(57) **CLAIM**

The ornamental design for an applicator, as shown and described.

DESCRIPTION

FIG. 1 is a perspective view of an applicator; FIG. 2 is a front elevation view thereof; FIG. 3 is a rear elevation view thereof; FIG. 4 is a side elevation view thereof; FIG. 5 is an opposite side elevation view thereof; FIG. 6 is a top plan view thereof; and, FIG. 7 is a bottom plan view thereof.
The broken line showings of the applicator are included for the purpose of illustrating portions of the article and form no part of the claimed design.

1 Claim, 4 Drawing Sheets

US D999,033 S

Page 2

Related U.S. Application Data

continuation of application No. 29/386,483, filed on Mar. 1, 2011, now Pat. No. Des. 670,982.
